UNITED STATES PATENT OFFICE.

JAMES A. LYONS, OF KNOXVILLE, TENNESSEE.

CURTAIN-FIXTURE.

No. 796,137.

Specification of Letters Patent.

Patented Aug. 1, 1905.

Application filed January 12, 1905. Serial No. 240,808.

To all whom it may concern:

Be it known that I, JAMES A. LYONS, a citizen of the United States, residing at Knoxville, in the county of Knox and State of Tennessee, have invented a new and useful Improvement in Curtain-Fixtures, of which the following is a specification, reference being had to the accompanying drawings.

My invention relates to curtain-fixtures, and particularly to that class of window-curtain fixtures in which provision is made for the vertical adjustment of a horizontal spring-roller upon which the curtain or shade is rolled, the object being to secure light and ventilation from above the curtain when desired.

The present invention is an improvement upon the invention which is the subject-matter of Letters Patent of the United States Nos. 739,889 and 739,890, granted to me September 29, 1903.

In the accompanying drawings, Figure 1 is a front elevation of a fixture embodying my improvement. Fig. 2 is an end elevation of the construction shown in Fig. 1. Fig. 3 is a front elevation of one of the upper supporting devices. Fig. 4 is a side elevation of the structure shown in Fig. 3 looking toward the right. Fig. 5 is a side elevation of the structure shown in Fig. 3 looking toward the left. Fig. 6 is a perspective view of the cord-supporting stirrup shown in Figs. 3, 4, and 5. Fig. 7 is a front elevation of the right-hand portion of the roller-supporting yoke. Fig. 8 is an end elevation of the structure shown in Fig. 7. Fig. 9 is a vertical cross-section on the line 9 9 of Fig. 7 looking in the direction of the arrow. Fig. 10 is a section on the line 10 10 of Fig. 7. Fig. 11 is a plan of the structure shown by Fig. 7. Fig. 12 is an enlarged front elevation of a fastening device. Fig. 13 is a similar side elevation.

Referring to said drawings, 1 is the window-casing.

2 is a curtain-roller.

3 is a yoke comprising a yoke-bar 3^a and brackets 4 4, applied to the ends of the yoke-bar and having bearings for supporting the shade-roller in the usual manner.

5 and 6 are supporting-cords extending upward from the yoke, the cord 5 passing through the support 7 and thence through the support 8 and the cord 6 passing only through the support 8. Below the support 8 said two

CORDS are joined together by knotting or in any other suitable manner. The cable 10 thus formed is extended downward along the window-casing and adjustably secured to a suitable fastening device 11. Obviously the cable 10 may be a single cord. From this description it will be understood that by drawing said cable downward the supporting-cords 5 and 6 will be drawn upward and that such upward movement involves the upward movement of the yoke 3 and the roller 2.

The cords 5 and 6 and the cable 10 may be of any suitable form, and in place of what is usually termed "cord" braid, wire, or chain may be used. The fastening device 11 may be of any suitable form adapted to engage the cable 10 at such points as may be desired, and said fastening device may be secured to the window-frame in any suitable manner. The form shown is a tube, (preferably flaring at each end,) through which the cable passes. The lower portion of said tube is provided with a V-shape notch 11^a, into which the cable 10 may be drawn. The knots 10^a on said cable facilitate the engagement of the cable in said notch. Said fastening device is shown in enlarged detail in Figs. 12 and 13.

The supports 7 and 8 may be of any desired form adapted to support and guide the cords 5 and 6. In the drawings I have shown preferred forms, consisting, respectively, of an ordinary roller-bracket 7^a and 8^a and a one-piece wire stirrup 7^b and 8^b, the bracket 7^a being applied to the upper portion of a window-casing just as it is ordinarily applied to receive the ordinary spring-actuated shade-roller and the stirrups being applied to said brackets. This form of support is desirable, because it facilitates the application of my improvement to windows already equipped with the ordinary non-shiftable spring-actuated shade-roller, for the roller may be lifted out of its stationary brackets and moved down into my yoke and the stirrups applied to said stationary brackets without changing the latter and without attaching any other mechanism to the upper portion of the window-casing, said wire stirrups being in themselves sufficient not only for the supporting and guiding of the cords 5 and 6, but also for the supporting of the upper ends of the guide-cords, to be hereinafter described. Said stirrups 7^b and 8^b are identical, excepting that

the former is adapted for the left-hand side and the latter for the right-hand side of the window; but making said stirrups right and left is only a matter of preference and notes-ential. A detailed description of the stirrup 8^b is sufficient for both. At its middle it has the downward U-shape fold 8^c to be applied to the left-hand side of the adjacent bracket. The forward arm is bent laterally toward the left and downward to form a hook 8^d, adapted to extend through the bearing B of the adjacent bracket. The rear arm of said U is bent laterally and downward, so as to ex-tend across the rear portion of said bracket, and thence downward to form an inverted-U-shape hook or fold 8^e, embracing the two sides of the upper portion of said bracket. When made in the form thus far described, said stirrup is complete for the supporting and guiding of the cords 5 and 6. To also adapt said stirrup to support the upper end of the adjacent guide-cord, the portion of the wire forming the hook 8^c is extended laterally and then upward to form a U-shape hook 8^f. In the stirrup 7^b the lateral direction of the hooks 7^d, 7^e, and 7^f (corresponding, respectively, to the hooks 8^d, 8^e, and 8^f) is toward the right.

The brackets 4 are integral with a foot 4^a, and said foot is integral with a sleeve 4^b, sur-rounding the yoke-bar 3^a. Said sleeve may be secured at any position along the length of the yoke-bar by means of a nail or screw or similar device 4^c, extending through the sleeve 4^b into said bar, preferably from above.

The yoke is provided at each end with a suitable passage for the lower ends of the sup-porting-cords. Such a passage may be con-veniently formed by forming in the yoke-bar 3^a, preferably in its lower face, a channel 3^b, where the sleeve 4^b surrounds said bar, and the adjacent cord 5 or 6 extends downward across the end of the yoke-bar and thence laterally through said channel and sleeve. Said channel is preferably formed along the entire length of the yoke-bar in order that the brackets 4 may be moved horizontally upon said bar to fit any length of shade-roller, the portion of said bar extending be-yond the sleeve 4^b being then cut off. This construction is of practical value, because it adapts a yoke-bar of maximum length to be applied to windows of any width.

The cords 5 and 6 after passing through the sleeve 4^b, as already described, may be se-cured in any suitable manner so as to suspend the yoke horizontally. I have found it de-sirable to provide an adjustable attachment for the lower ends of said cords in order that the yoke may be readjusted at any time when one end becomes lowered by the stretching of one of said cords 5 and 6 or when it is desired to raise or lower the entire yoke relative to said cords, as when the knots 10^a do not en-gage at the right elevation to bring the shade

to the exact desired lower or upper limit. In the drawings, 11^b is a clamp horizontally ad-justable upon the yoke-bar, and the end of the cord is attached to said clamp. Said clamp may be constructed in various forms; but for the sake of economy I prefer to make it of a single piece of wire, as shown by the drawings. The main portion of said clamp is U form and embraces the bottom and sides of the yoke-bar, while the upper end of each upright arm of the U is bent laterally away from the adjacent cord to form an arm 11^a, bearing upon the upper face of the yoke-bar. The adjacent supporting-cord is tied to the lower portion of said clamp. The construction de-scribed adapts said clamp to engage or grip said bar when strain is put upon said cord. The upper point of engagement is between the ends of the arms 11^a and the upper face of the yoke-bar, and in order to augment such engagement said ends are preferably made angular or pointed. When the clamp is engaged by the hand and inclined, as shown in the drawings, it may be readily moved in either direction on said bar. Having these clamps as a part of the apparatus, it is unnec-essary to take pains to have the two sup-porting-cords 5 and 6 precisely equal in length from the supports 7 and 8 downward or to have said supports precisely in the same hori-zontal line. Said supports may be placed only approximately in the same horizontal line and said cords may be only approxi-mately even in length when they are applied to the yoke, and then they may be accurately adjusted by means of said clamps after the shade is in place.

A guide-cord 12 is placed at each side of the window-casing, the upper end of each cord being secured to the adjacent hook 7^c or 8^c and the lower end being secured to any suit-able stationary device attached to the window-casing. The drawings show a stirrup 13 se-cured to the lower end of each of said cords and said stirrups extending around a nail 14, which extends horizontally outward from the window-casing. Said stirrup is preferably formed of a single piece of wire bent into U form, with the upper portion nearly closed and the upper ends of the wire bent laterally in the plane of the stirrup to form hooks 13^a to be engaged by a loop 12^a, formed on the said guide-cord. As a means for securing the yoke 3 slidably to said guide-cords, wire loops 15 are applied to the sleeve 4^b, as shown in detail by Figs. 7, 8, 10, and 11. Said guide consists of a single piece of wire folded upon itself and around the rear, bottom, and a por-tion of the front of said sleeve and extending through apertures 4^d in the foot 4^a, by which construction said guide is effectively secured to said yoke. The upper end of said guide is preferably curved rearward, as clearly shown by Fig. 8. The guide-cord extends

through said loop and behind said sleeve and foot. The yoke is free to move up and down upon said cords, but is held by them against lateral movement. While sliding up and down each foot 4^a bears only against the adjacent guide-cord and the loop 15 does not make contact with the window - casing, because the weight of the shade and roller tilt the upper portion of the yoke outward away from the window, so that said guide-loop clears the window-casing.

The importance of the several portions of my present invention consists in their simplicity and economy in manufacture. The stirrups 7^a and 8^a can be manufactured at very small cost and with simple tools or machines, and they make possible the suspension of the shiftable shade-roller from the ordinary stationary brackets, as above indicated. A maximum length of yoke-bar having the channel 3^b may be readily fitted to any length of shade-roller. The clamps 11^b are made of wire and are of a form suited to economical manufacture, and the form of said clamps is such as to permit the easy application of the supporting-cords. This may be accomplished by merely looping the supporting-cord through the clamp, as shown by Figs. 7 and 9, and the stirrups 7^a and 8^a are adapted for the attachment of the upper end of the guide-cords after said ends have been tied to form an ordinary loop 12^b, and the stirrups 14 are of such form as to adapt them to be secured to the lower end of the guide-cord after the latter has been tied to form a loop 12^a. Additional tension may at any time be given to either of said guide-cords by giving its loop 12^a additional turns around the hooks 13^a.

I claim as my invention—

1. In a curtain-fixture, the combination with roller-brackets, 7^a and 8^a, a yoke, supporting-cords, 5 and 6, and cable, 10, of U-shape stirrups having hooks for engaging said roller-brackets, substantially as described.

2. In a curtain-fixture, the combination with roller-brackets, 7^a and 8^a, a yoke, supporting-cords, 5 and 6, cable, 10, and guide-cords, 12, of U-shape stirrups having hooks for engaging said roller-brackets, and the upper ends of said guide-cords, and mechanism for engaging the lower ends of said guide-cords, substantially as described.

3. In a curtain-fixture, the combination with roller-brackets, 7^a and 8^a, a yoke, supporting-cords, 5 and 6, and cable, 10, of U-shape stirrups having hooks for engaging said roller-brackets, and clamps shiftable upon said yoke for adjustably securing said cords, 5 and 6, substantially as described.

4. In a curtain-fixture, the combination with a yoke comprising brackets for supporting a shade-roller and having passages for supporting-cords, of upper stationary supports, supporting-cords, 5 and 6, applied to said sup-

ports and extending through said passages on said yoke, and mechanism for adjustably securing said cords to said yoke, substantially as described.

5. In a curtain-fixture, the combination with a yoke comprising brackets for supporting a shade-roller and having passages for supporting-cords, of clamps slideable upon said yoke, upper stationary supports, supporting-cords, 5 and 6, applied to said supports and extending through said passages and secured to said clamps, substantially as described.

6. In a curtain-fixture, the combination with roller-brackets, 7^a and 8^a, a yoke comprising a yoke-bar, and brackets, feet, and sleeves integral with each other, of U-shape stirrups having hooks for engaging said roller-brackets, supporting-cords, 5 and 6, extending through said stirrups and through said sleeves, and mechanism for adjustably securing said cords to said yoke, substantially as described.

7. In a curtain-fixture, the combination with roller-brackets, 7^a and 8^a, a yoke, supporting-cords, 5 and 6, and cable, 10, of U-shape stirrups, having hooks for engaging said roller-brackets, said yoke comprising a yoke-bar, and brackets, feet, and sleeves integral with each other, supporting-cords extending through said sleeves, and clamps secured to said cords and adjustably applied to said bar, substantially as described.

8. In a curtain-fixture, the combination with a yoke comprising a channeled yoke-bar, and brackets, feet, and sleeves integral with each other, of upper stationary supports, supporting-cords, 5 and 6, applied to said supports and extending through said passages in said yoke, and mechanism for adjustably securing said cords to said yoke, substantially as described.

9. In a curtain-fixture, the combination with a yoke comprising a channeled yoke-bar, and brackets, feet, and sleeves integral with each other, of upper stationary supports, supporting-cords, 5 and 6, applied to said supports and extending through said passages in said yoke, and clamps slideable upon the yoke-bar for the adjustment of said supporting-cords, substantially as described.

10. In a curtain-fixture, the combination with a yoke comprising brackets for supporting a shade-roller and having passages for supporting-cords, of clamps embracing the bar of said yoke and having lateral arms bearing upon the upper face of the yoke, upper stationary supports, supporting-cords, 5 and 6, applied to said supports and extending through said passages and secured to said clamps, substantially as described.

11. In a curtain-fixture, the combination with a yoke comprising a yoke-bar, and brackets, feet, and sleeves integral with each other, and feet having apertures, 4^a, wire loops extending through said apertures and partially embracing said sleeves, of guide-cords ex-

tending through said loops and behind said sleeves and feet, mechanism for securing the upper and lower ends of said cords, supporting-cords, 5 and 6, applied to said yoke, and upper stationary supports for said supporting-cords, substantially as described.

In testimony whereof I have signed my name,

in presence of two witnesses, this 2d day of January, in the year 1905.

JAMES A. LYONS.
